UNITED STATES PATENT OFFICE.

ERNESTO ANSELMI, OF VITERBO, ITALY.

PORTABLE APPARATUS AND PROCESS FOR VULCANIZED REPAIRS OF PNEUMATIC TIRES.

No. 918,943.

Specification of Letters Patent.

Patented April 20, 1909.

Application filed May 17, 1907. Serial No. 374,293.

To all whom it may concern:

Be it known that I, ERNESTO ANSELMI, a subject of the King of Italy, residing at Viterbo, Italy, have invented certain new and useful Improvements in Portable Apparatus and Processes for Vulcanized Repairs of Pneumatic Tires, of which the following is a specification.

The present invention refers to a portable apparatus which allows all vulcanized repairs for damages in pneumatic tires in general, and in automobile tires more particularly, to be made without the aid of special workshops. The said repairs may be made anywhere, in a short time, easily and with the best results.

The accompanying drawing shows a practical application of the said invention.

Figure 1 is a perspective view of the apparatus at work. Fig. 2 shows the heat conducting plate. Fig. 3 is a vertical section of the apparatus. Fig. 4 is a perspective view of a case in which not only the apparatus but all the accessories and all the reserve material are kept.

The apparatus is made of the following parts:

1. A small case *a* (Fig. 4) designed to contain all that is necessary to accomplish the repair and to act as prop to the whole apparatus while at work. The dimensions of the said case vary, of course, according to circumstances, but it is best to use the following ones, given here as an example, without, however, considering it absolutely necessary to adopt them; the said dimensions are $11 \times 11 \times 23$ centimeters.

2. A metal vise *b* consisting of a strong curved bar in the shape of a *U*; the screw pivot *c* is inserted in one of its branches, near the curve, which allows the vise to be fixed horizontally at the bottom of the case when turned upside down where a hole is made for the purpose (Fig. 3). The other branch of the vise has pressing screws *d* (three are seen in the drawing).

3. A small alcohol or benzin lamp *e*.

4. A special thermometer *f* which can bear no scale but on which a very clear sign, preferably red and large, marks the temperature of 153° , which is the temperature necessary to the process I will explain later on.

5. The heat conductor *g* (Fig. 2) made of a plate either of copper or of any other suit-

able metal; this plate is furnished with an opening *h* in order to give passage to the gas of the lamp; near this opening *h* the tube *k* made of the same metal as the plate is secured, the said tube, destined to receive the thermometer *f* is full of paraffin. The surface of the plate on which the tube is secured as well as the latter, is covered with pasteboard *l* either made of amiantus or of any other matter of the same kind in order to protect them against too rapid a cooling.

Besides the utensils already described, other materials are still necessary and form part of the whole apparatus; they are held in the case and the way some of them are to be used is described later on together with the process, with reference to the drawing. The main materials are:

6. A tube of cement made of first class india rubber, that designed for stamps, dissolved in carbon disulfid to a fair density.

7. A set of small iron, lead or other suitable metal plates.

8. Some prepared pieces, made of an india rubber sheet previously vulcanized (cut, for instance, out of a pneumatic tire out of use) and of another india rubber sheet for stamps. The two sheets are placed one over the other and stuck together by means of the above said cement. Instead of the pieces made of two thin plates or sheets, as described above, one may also use, with advantage, some pieces formed by only one india rubber sheet, for stamps, which should always be of first class.

In order to repair any damage, the subsequent directions are to be followed; after having ascertained the nature of the damage, I select among the materials forming the set, a prepared piece of rubber of the necessary size, to cover the damage entirely, and to extend over beyond it for about the length of half a centimeter. A brush is then soaked in benzin and passed two or three times over the prepared piece of rubber, but on the gray side so as to revive it, and it is then left to dry. As said above, simple pieces of rubber may be used in an analogous way. The surface of the pneumatic tire to be repaired is then carefully rubbed with glass-paper on the place of the damage and a little distance around the same; a brush soaked in benzin is then passed over it several times until the said parts are perfectly clean. A given quantity of cement is

squeezed out of the tube and is spread carefully with one's finger, over the tire all around the perforation and along the spot of the damage. The cement is to be used freely. If the piece where the damage has been made has been wrenched off, a small piece of india rubber is applied in the opening (that piece may be cut out of a pneumatic tire out of use) while endeavoring to stop it up, one should be careful to coat the rims of the opening and those of the piece with some cement. It is then left to dry for a few minutes while the apparatus is put up. The case, is for that purpose, turned upside down and the screw pivot *c* is introduced into the opening made for the said purpose, and is firmly screwed there; the case acting as a support. This done, piece *m* is applied to the part of the pneumatic tire *n* where the damage previously covered with cement is found, the latter having grown hard. Care should be taken to ascertain that the piece covers the damage well, and that it presses it firmly. It is to be understood that the piece of rubber if it is the one made of two sheets, should be stuck on the gray side. A plate *o* is then selected of the due shape and size, furnished with an india rubber sheet *p* and placed under the pneumatic tire directly opposite the place to be repaired. A piece of vegetable parchment *q* is preferably placed on the adhering piece in order to prevent the piece under repair from being stained by the vulcanization; the lead-plate *r* is placed on the parchment, the said plate being of a size to project beyond the edges of the rubber piece; one end of the heating plate *g*, the upper surface of which has been coated with amiantus *l*, is placed on the lead plate between the branches of the vise. Care should be taken to ascertain that the various parts are directly and symmetrically one above the other. The screws *d* of the vise are then tightened, and therefore press gradually on the parts through the medium of an iron plate *o'*, special care being given not to choke the lateral folds *u* on the rim of the tube. The parts being in position the lamp *e* is lighted and placed under the free part of the heating plate projecting from the vise as shown in drawing (Figs. 1 and 3). In order to protect the pneumatic tire against the flame of the lamp an amiantus paste-board *s* is located on the tire toward the lamp. Preferably strips *t* of amiantus are also placed between the tire and the heat conductor *g*. The heat of the plate, causes the paraffin contained in the tube thereof to melt. As soon as it melts the thermometer *f* is introduced in the tube. The quicksilver column will soon be seen to rise and when it has reached the mark made on the tube, it will indicate that the temperature has reached to the point in which the vulcanization commences. By keeping the tem-

perature even for about 12 minutes, which is easily obtained by taking away and then replacing the lamp, according to the indications given by the quicksilver column, a perfect vulcanization of the piece is obtained, so that it is firmly secured to the tire. A slight characteristic odor produced by the vulcanizing of the india rubber easily perceptible if inhaled on approaching to the preparation, shows that the operation is well managed. At the end of 12 minutes, the flame is extinguished. When sufficiently cold so that the hand will be able to stand the contact with the different parts of the instrument (which will be about 10 minutes) the screws are loosened, the pneumatic tire is taken out of the vise, the plates removed, and after having freely sprinkled the parts with talc the repair is made. All there is to be done now is to undo the apparatus and to replace it in the case. The time necessary for a repair is about 35 minutes.

Having now particularly described and ascertained the nature of my said invention and in what manner the same is to be performed, I declare that what I claim is:

1. A portable apparatus for repairing pneumatic tires, comprising a support in the form of a case for containing the several parts of the apparatus when not in use, a U-shaped bar having one member provided with means whereby it may be secured to the case and its other member provided with screws, metal plates adapted to be placed on opposite sides of the tire, a heating plate covered with asbestos, said plate being apertured and provided with a tube adapted to contain paraffin, a thermometer adapted to be placed in the said tube, the tire and plates being adapted to be clamped between the members of the said bar with a portion of the heating plate projecting therefrom, and a lamp adapted to be placed under the projecting portion of the said plate.

2. A portable apparatus for repairing pneumatic tires, comprising a support in the form of a case for containing the several parts of the apparatus when not in use, a vise adapted to be secured to the case, metal plates adapted to be placed above and below the tire, a heating plate apertured and provided with a tube projecting from its upper surface and adapted to contain paraffin, a thermometer adapted to be placed in the tube, the tire and plates being adapted to be clamped in the vise with a portion of the heating plate projecting therefrom, and a lamp adapted to be placed under the projecting portion of the said plate.

3. In an apparatus for repairing pneumatic tires, the combination with a vise, of a heating plate having an aperture therein and provided with a tube projecting from its upper surface, said tube being adapted to contain paraffin and to hold a thermometer, the

said plate being clamped in the vise with the tire and having a portion projecting beyond the vise, and a lamp for heating the said plate.

5 4. In an apparatus for repairing pneumatic tires, a heating plate covered with asbestos, and provided with an aperture and with a tube projecting from its upper surface.

In witness whereof I, said ERNESTO ANSELMI have signed this specification, at Rome 10 in the Kingdom of Italy, this 2nd day of May 1907

ERNESTO ANSELMI.

In presence of—

A RAGGI,
T. I. BENEDETTI.
